UNITED STATES PATENT OFFICE.

NORRIS PANGBURN, OF CASTLETON-ON-HUDSON, NEW YORK.

DESIGN FOR A GRAVE MARKER.

Application filed May 29, 1929. Serial No. 31,449. Term of patent 14 years.

To all whom it may concern:

Be it known that I, NORRIS PANGBURN, a citizen of the United States, residing at Castleton-on-Hudson, in the county of Rensselaer and State of New York, have invented a new, original, and ornamental Design for Grave Markers, of which the following is a specification, reference being had to the accompanying drawing, forming part thereof.

In the drawings

Figure 1 is a front view in elevation of the grave marker, showing my new design, Figure 2 is a side view in elevation, and Figure 3 is a top plan view.

I claim:

The ornamental design for a grave marker, as shown.

NORRIS PANGBURN.
